UNITED STATES PATENT OFFICE

2,485,213

ACTUATOR BUTTON

Frederick A. Niemann, Chicago, Ill., assignor to
Felt & Tarrant Manufacturing Company, Chi-
cago, Ill., a corporation of Illinois

Application April 23, 1945, Serial No. 589,801

9 Claims. (Cl. 197—102)

1

This invention relates to improvements in actuator buttons and has for an object to provide a button, economical of manufacture, easy to attach to and detach from an actuated element such as a stem of an actuatable member of a calculating machine, typewriter, switch, or the like.

This and other objects will be more fully set forth and made apparent in the following specification and accompanying drawings of which

Fig. 1 is a plan view of a portion of a computing machine showing one of my buttons applied thereto;

Fig. 2 is a side elevation thereof showing my actuator button and an associated stem in depressed position;

Fig. 3 is a side elevation drawn to larger scale of a button and a portion of an associated stem, the casing of the apparatus shown in Fig. 1, being shown in section;

Fig. 4 is a vertical section drawn to larger scale, taken along the line 4—4 of Fig. 1;

Fig. 5 is a horizontal section along the line 5—5 of Fig. 4; and

Fig. 6 is a vertical, sectional view similar to that of Fig. 4 showing my improved button in detached relation to the stem.

Like numerals refer to like elements throughout the drawing, in which, 10 indicates generally a button embodying my invention, 11 designates the button head, and 12 the cap of plastic or other suitable material sufficiently resilient for gripping attachment to the head 11. The numeral 13 indicates generally an actuatable stem which may be an element of a calculating machine, as illustrated in the drawings, or of other devices in which my improved button may be satisfactorily incorporated.

The head 11 is provided with a vertical slot 11a extending from top to bottom in the form shown and with a peripheral groove 11b with which communicate the recess 11d and cavity 11c, the former being extended into communication with the slot 11a, as illustrated in Figs. 4, 5, and 6, for example, with limiting shoulders 11x at the junction thereof.

The upper portion 11e of head 11 is of reduced diameter and provided with peripheral grooves 11f tapered inwardly from bottom to top as illustrated in Figs. 4 and 6.

The cap 12 is desirably provided with a slight concavity or depression 12a for finger engagement and on the bottom is provided with a cylindrical recess 12b very slightly less in diameter than the external diameter of the reduced portion 11e of head 11. By selecting material for

2

the cap 12 of slight inherent resilience, such as plastics which are now in common use, the cap may be readily forced on the head 11 as illustrated in Figs. 4 and 6 and will be held in assembled relation therewith unless it be desired to disassemble the two parts. The grooves 11f serve to enhance the gripping engagement of the cap 12.

A resilient split ring 14 is removably mounted in the groove 11b and has an inwardly bent extremity 14a constructed to enter the cavity 11c (see Fig. 5).

Mounted in the recess 11d is the latching ball or member 15 normally retained in such recess by the ring 14 as illustrated. The construction and arrangement of the ball and ring are such that the latter will normally urge and yieldingly tend to hold the ball 15 at the inner end of recess 11d which is shouldered at 11x, as stated, to limit the inward movement of such ball.

In the association illustrated in the accompanying drawing, the stem 13 projects through the top of casing 20, a small slot 20a being provided therein to permit movement of such stem relative to the casing. The stem is shouldered at 13a and provided with the upwardly extending reduced end 13b in which is provided a recess 13c having the upwardly inclined upper side 13d. The stem is likewise chamfered at the upper end at 13e. The stem, as illustrated, is of flat metal of slightly less thickness than the width of slot 11a, and the width of the reduced upper end 13b is slightly less than the horizontal length of the slot 11a. To assemble the button upon the stem 13, it is merely necessary to insert the upper end of the stem in the bottom of the slot 11a and thereafter push the button downwardly upon the stem until the latching ball 15 sets in the recess 13c. The chamfered extremity 13e of the stem permits relatively easy displacement of the ball 15 during its attachment to the stem, and, when it is desired to remove the button from the stem, a slight pull will permit such detachment, as will be obvious. The inclined upper side 13d of the recess 13c will ease this detachment.

With my improved button, it is a simple matter to attach or detach the button to permit lifting of the casing 20 from the enclosed mechanism so that a relatively small slot 20a in the casing may be utilized with lesser possibility of entrance of dust, dirt, and the like.

It will be apparent that my invention is susceptible of modification and improvement, and I do not wish to be restricted to the form shown and described except as limited thereto by the ap-

pended claims properly interpreted with respect to the prior art.

What I claim is:

1. The combination of an actuatable key stem for a business machine having a recess therein, and a button comprising a head constructed for mounting upon said stem, said head being provided with a latching member movably mounted therein and movable into the recess of said stem, and means yieldingly to hold said latching member in said recess.

2. An actuator button comprising a head having a slot therein, and a recess, a latching member movably mounted in said recess, and means yieldingly securing said latching member in said recess and projecting into said slot.

3. An actuator button comprising a head having a slot therein, and a recess, a latching member movably mounted in said recess, and means yieldingly securing said latching member in said recess and projecting into said slot, said means comprising a resilient ring.

4. An actuator button comprising a head having a slot therein, and a recess, a latching member movably mounted in said recess, and means yieldingly securing said latching member in said recess and projecting into said slot, said means comprising a resilient ring, said head being provided with a groove for said ring.

5. An actuator button comprising a head, said head being provided with a slot therein and a groove surrounding said slot, said head being further provided with a recess extending between said groove and slot, and with a recess communicating with said groove, a latching member movably mounted in said first recess, and a spring locking ring mounted in said groove and having a portion extending into said second recess, said ring being constructed and arranged yieldingly to urge said latching member into said slot.

6. In combination, a stem having a notch therein, an actuator button having a slot for receiving said stem and being provided with a recess communicating with said slot and alignable with said notch in said stem when in assembled relation thereto, latching means carried by said button in said recess, and means also carried by said button yieldingly to urge said latching member into said notch in said stem.

7. An actuator button comprising a head having peripheral grooves tapered inwardly from bottom to top, and a cap mounted thereon, said cap being recessed for engagement with said head and formed of material of sufficient inherent resilience to permit forcing thereof upon said head

into gripping engagement with said peripheral grooves.

8. An actuator button comprising a head, said head being provided with a slot therein and a groove surrounding said slot and a recess extending between said groove and said slot and a second recess communicating with said groove, a latching member movably mounted in said first recess, and a split spring locking ring mounted in said groove and having one end thereof extending into said second recess, said ring engaging said latching member adjacent the other end thereof to urge the latching member into said slot, and said second recess being spaced circumferentially of said groove from said first recess a distance necessary to insure the application of a predetermined force by said ring against said latching member.

9. In combination, a stem having a notch therein, an actuator button having a slot for receiving said stem and being provided with a recess communicating with said slot and alignable with said notch in said stem when the stem and button are in assembled relation, latching means carried by said button in said recess, said button having a second recess spaced circumferentially thereof from said first recess, and a split ring carried by said button and engaging said latching member yieldingly to urge the same into said notch in said stem, one end of said ring engaging in said second recess to prevent circumferential displacement of said ring to insure the application thereby of a predetermined force to said latching member for resisting displacement thereof from said notch.

FREDERICK A. NIEMANN.
